V. GUINZBURG
POWDER PUFF HOLDER
Filed Oct. 11, 1922

INVENTOR

Victor Guinzburg
BY HIS ATTORNEY
Joseph L. Levy

UNITED STATES PATENT OFFICE.

VICTOR GUINZBURG, OF NEW YORK, N. Y., ASSIGNOR TO I. B. KLEINERT RUBBER COMPANY, OF NEW YORK, N. Y., A CORPORATION OF NEW YORK.

POWDER-PUFF HOLDER.

Application filed October 11, 1922. Serial No. 593,825.

To all whom it may concern:

Be it known that I, VICTOR GUINZBURG, a citizen of the United States, and a resident of the city, county, and State of New York, have invented a certain new and useful improvement in Powder-Puff Holders, of which the following is a specification.

This invention relates to a convenient form of holder or pouch for receiving the powder puff and holding the same, whereby said puff is kept clean and sanitary at all times.

An object of this invention is to provide a puff holder which will be simple in construction, substantially small in size and of such material as to render it clean and sanitary.

With these objects and other objects which may hereinafter appear, in view, I have devised the particular arrangement of parts hereinafter set forth and more particularly pointed out in the claim appended hereto.

Reference is to be had to the accompanying drawing, forming a part hereof, in which—

Figure 1 is a perspective view of a powder puff made in accordance with my invention showing one of the flaps in open position;

Figure 2 is a front elevation of the holder in closed position;

Figure 3 is a side elevation of the holder, and

Figure 4 is a sectional view on the line 4—4 of Figure 2, looking in the direction of the arrows.

Throughout the various views of the drawings, similar reference characters designate similar parts.

In the preferred embodiment of my invention as shown in the accompanying drawing, 1 indicates one of the faces of the holder and 2 indicates a similar face.

These faces or sections may be made of any suitable washable or sanitary material, such as sheet rubber or the like.

Both of the sections 1 and 2 are provided with a reinforcing binding 3 extending about their edge. Said binding is preferably of some inexpandable material and is secured to the edges of the sections 1 and 2 by means of a line of stitching 4. The two sections 1 and 2 are placed together and a line of stitching 5 extends through both bindings for the greater portion of the circumference of the two sections 1 and 2 to secure them together and form the pouch. The mouth or opening 8 is preferably smaller than the diameter of the pouch but is expandable due to the expandable nature of the sheet rubber disks which form the sides of the pouch.

The line of stitching 5 does not extend completely around the sections 1 and 2 leaving unsecured portions, forming flaps 6 and 7, between which the mouth or opening 8 of the pouch is provided.

A means for detachably uniting the two flaps 6 and 7 thus formed consists of the cooperating snap fastener members 9 and 10, one of which is provided on each binding.

From the foregoing, it will be seen that I have provided a powder puff holder extremely convenient in size and which may be readily carried and will completely enclose a powder puff, keeping the same clean and sanitary at all times.

Having described my invention, what I claim is:

An article of the class described comprising a pair of flat, substantially circular disks of expandable material, said disks being secured together at their edges for a portion of their circumference, leaving an expandable opening of less length than the diameter of the disks, and detachable means for uniting together the unsecured portions of the disks to close the opening.

Signed at the city, county and State of New York, this 3rd day of October, 1922.

VICTOR GUINZBURG.
